UNITED STATES PATENT OFFICE.

WILLIAM M. WHITE, OF MILWAUKEE, WISCONSIN.

WEARING PLATE FOR HYDRAULIC MACHINES.

Application filed June 5, 1926. Serial No. 113,908.

This invention relates generally to an improved method of protecting the surfaces of fluid conducting conduits or the like against excessive wear, and relates more specifically to improvements in the construction of and in the mode of attaching and removing wear plates for hydraulic machines such as turbines or pumps.

An object of the invention is to provide a new and useful protective lining for hydraulic conduits or the like. Another object of the invention is to provide an improved method of securely fastening liner plates in place, and for effecting convenient removal thereof when replacement becomes desirable. A further object of the invention is to provide improved wear plates for the inlet casings of hydraulic turbines of the type wherein the water is delivered toward the rotor past an annular series of adjustable guide vanes. These and other objects and advantages of the invention will be apparent from the following description.

A clear conception of an embodiment of the invention and of the mode of applying and removing wear plates constructed in accordance therewith, may be had by referring to the drawing accompanying and forming a part of this specification in which like reference characters designate the same or similar parts in the several views.

Fig. 1 is a fragmentary central vertical section through a hydraulic turbine having the improved lining plates applied therein.

Fig. 2 is a horizontal section through the casing of the turbine disclosed in Fig. 1, the section being taken along the line II—II of Fig. 1 looking downwardly.

Fig. 3 is a fragmentary sectional view showing details of the improved lining ring fastening.

The hydraulic turbine to which the invention has been applied by way of illustration, comprises in general a rotor 2 consisting of an annular series of vanes secured to a central hub and surrounded by a shroud ring 4; a casing comprising an upper element 11, a lower element 12 and a speed ring 7 enclosing the turbine rotor 2; an annular series of adjustable inlet guide vanes 8 having pivots 9, 10 journaled in the casing elements 11, 12 respectively; and a main shaft 5 secured to the rotor 2 and coaxing with a guide bearing 6 associated with the turbine casing. The adjustable inlet guide vanes 8 are simultaneously movable by

means of mechanism associated with actuating arms 17 secured to the upper pivots 9, and the vanes 8 are swingable about the pivots 9, 10 to control the flow of fluid from the speed ring 7 to the rotor 2.

The hub of the rotor 2 has an annular flange 3 extending away from the rotor axis and in close proximity to the upper casing element 11. The casing element 11 is provided with an annular recess 20 which coacts with an annular series of segmental plane wearing plates 13, these wearing plates being penetrated by the upper vane pivots 9. An annular series of segmental curved retainer plates 15 coact with the inner edges of the wear plates 13 and extend in close proximity to the periphery of the flange 3 thereby providing a running joint.

The rotor shroud ring 4 is provided with a peripheral wearing ring 22 extending in close proximity to the lower casing element 12. The casing element 12 is provided with an annular recess 21 which coacts with an annular series of segmental plane wearing plates 14 through which the lower vane pivots 10 extend. An annular series of segmental curved retainer plates 16 coact with the inner edges of the wear plates 14 and cooperate with the rotor wearing ring 22 to provide a running joint.

The segment shaped plane wear plates 13, 14 are forced into the recesses 20, 21 respectively, by means of a radial wedge 19 as shown in Fig. 2, the wedge 19 being held in place by the overlapping edges of the adjacent wear plates 13, 14 as indicated by the dotted lines. The wedge 19 is driven outwardly between the ends of adjacent segments thereby urging the wear plates into the annular recess of the adjacent casing element. The segmental curved retainer plates 15, 16 are formed with wedge surfaces engageable with similar surfaces formed upon the inner edges of the wear plates 13, 14, and the retainer plates 15, 16 are rigidly attached to the adjacent casing elements 11, 12 by means of screws 18 as shown in Fig. 3. The liner plates 13, 14 are held in place solely by the overlapping portions of the casing elements 11, 12 and of the retainer plates 15, 16, and obviously cooperate with the end surfaces of the movable guide vanes 8, while the liner plates 15, 16 cooperate with the movable flange 3 and wearing ring 22 of the rotor 2, to protect all of the wearable surfaces.

During normal operation of the turbine, the guide vanes 8 are adjusted to admit water from the speed ring 7 to the rotor 2 in an obvious manner. The rotor 2 imparts 5 rotary motion to the main shaft 5 which may be associated with an energy absorber in a well known manner. Due to the adjustment of the guide vanes 8, considerable 10 wear takes place between the ends of the vanes 8 and the adjacent casing elements, and this wear is taken up by the removable lining plates 13, 14. Due to rotation of the rotor 2, considerable wear also takes 15 place between the rotor flange 3 and wearing ring 22 and the adjacent casing elements. This wear is taken up by the removable lining plates 15, 16 cooperating with the flange 3 and with the ring 22 respectively.

As the lining plates 13, 14, 15, 16 may 20 eventually wear to such an extent that replacement thereof becomes desirable, these plates may readily be removed by separating the casing elements 11, 12 and removing the 25 guide vanes 8. After the guide vanes 8 have been removed, the segmental plates 15, 16 may be removed by releasing the screws 18. When the plates 15, 16 have been withdrawn the wedge 19 may be withdrawn, whereupon the plates 13, 14 are freely 30 removable from within the retaining recesses 20, 21. The mode of assembling the structure may be effected by reversing the steps 35 of removal, and both removal and assemblage may obviously be quickly effected with minimum delay in operation of the turbine unit.

It should be understood that it is not desired to limit the invention to the exact 40 details of construction and to the precise mode of applying and of removing the improved liner plates, for various modifications within the scope of the claims may occur to persons skilled in the art.

It is claimed and desired to secure by Letters Patent:

1. In combination, a rotor, a casing forming a fluid conducting conduit communicating with said rotor, an annular series of 50 segment shaped plates providing a lining for said casing adjacent to said conduit, and means cooperable with the adjacent ends of two of said plates for forcing adjoining ends of other of said plates into intimate contact with each other.

2. In combination, a rotor, a casing forming a fluid conducting conduit communicating with said rotor, an annular series of 60 segment shaped plates providing a lining for said casing adjacent to said conduit, and a radially adjustable wedge for forcing the adjoining ends of said plates into intimate contact with each other.

3. In combination, a rotor, a casing forming a fluid conducting conduit communicating with said rotor, an annular series of 65

segment shaped wearing plates providing a lining for said casing extending parallel to said conduit, and an annular series of segment shaped retaining plates coacting with edges of said wearing plates and extending transversely away from said conduit.

4. In combination, a rotor, a casing forming a fluid conducting conduit extending transversely of the axis of and communicating with said rotor, an annular series of 75 segment shaped plane plates providing a lining for said casing extending parallel to said conduit, and an annular series of segment shaped curved plates coacting with the edges of said plane plates and extending laterally away from said conduit.

5. In combination, a rotor, a casing forming a fluid conducting conduit extending transversely of the axis of and communicating with said rotor, an annular series of 85 segment shaped plane plates having outer edges disposed within a recess of said casing and providing a lining therefor adjacent to said conduit, means for forcing the adjoining ends of said segments into intimate contact with each other, and an annular series of segment shaped curved plates coacting with the inner edges of said plane plates and extending laterally away from 90 said conduit.

6. In combination, a rotor, a casing forming a fluid conducting conduit communicating with said rotor, an annular series of 100 guide vanes spanning said conduit, an annular series of segment shaped plates providing a lining for said casing adjacent to the corresponding ends of said vanes, and means cooperable with the adjacent ends of two of said plates for forcing the adjoining 105 ends of other of said plates into intimate contact with each other.

7. In combination, a rotor, a casing forming a fluid conducting conduit communicating with said rotor, an annular series of 110 guide vanes spanning said conduit, annular series of segment shaped plates providing linings for said casing adjacent to the opposite ends of said vanes, and a wedge for forcing the adjoining ends of said plates into intimate contact with each other.

8. In combination, a rotor, a casing forming a fluid conducting conduit communicating with said rotor, said casing having an 120 annular recess therein, a series of segment shaped plates coacting with said recess and providing a lining for said casing, and means cooperable with the adjacent ends of two of said plates for forcing the adjoining 125 ends of other of said plates into intimate contact with each other and with said casing recess.

9. In combination, a rotor, a casing forming a fluid conducting conduit communicating with said rotor, said casing having an 130

annular recess therein, an annular series of segment shaped wearing plates extending into said recess and providing a lining for said casing, means for forcing the adjoining ends of said plates into intimate contact with each other, an annular series of segment shaped curved plates formed to retain said wearing plates in coaction with said recess, and means for attaching said curved plates to said casing.

10. In combination, a casing having an annular recess therein, a series of wear plates coacting with said casing recess, and means for applying endwise pressure to some of said plates to force said series into intimate contact with said recess.

11. In combination, a rotor, a casing forming a fluid conducting conduit communicating with said rotor and having an annular

undercut recess therein, an annular series of wearing plates providing a lining for said casing and having outer edge portions extending into said recess, and an annular series of retaining plates having wedge surfaces cooperable with the inner edge portions of said wearing plates to retain said wearing plates in position.

12. In combination, a casing having an annular undercut surface forming a recess therein, a series of wearing plates having outer surfaces coacting with the undercut surfaces of said casing recess, and means for forcing some of said plates apart to retain said plate and casing surfaces in engagement with each other.

In testimony whereof, the signature of the inventor is affixed hereto.

WILLIAM M. WHITE.
